(57) **CLAIM**

The ornamental design for a dual tank container for spraying cleaning solution and removal of waste water from a fabric or floor cleaning operation, as shown and described.

DESCRIPTION

FIG. 1 is an upper side perspective view of a dual tank container for spraying cleaning solution and removal of waste water from a fabric or floor cleaning operation, showing my design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof;

FIG. 7 is a rear elevation view thereof; and,

FIG. 8 is a front perspective view thereof.

The broken line showing of hoses, spray gun, and canister in FIG. 8 is included for the purpose of illustrating portions of the dual tank container for spraying cleaning solution and removal of waste water from a fabric or floor cleaning operation and forms no part of the claimed design.
